(57) **CLAIM**

We claim an ornamental design for a dual laser device, as shown and described.

DESCRIPTION

FIG. 1 is a perspective view of one embodiment of the present invention;

FIG. 2 is a front view of the embodiment of FIG. 1;

FIG. 3 is a rear view of the embodiment of FIG. 1;

FIG. 4 is a right side view of the embodiment of FIG. 1;

FIG. 5 is a left side view of the embodiment of FIG. 1 and the opposite side of FIG. 4;

FIG. 6 is a top view of the embodiment of FIG. 1;

FIG. 7 is a bottom view of the embodiment of FIG. 1; and, FIG. 8 is a side perspective view of the embodiment of FIG. 1.

The dashed lines are included for illustrating environmental structure and form no part of the claimed design.
